UNITED STATES PATENT OFFICE

98,685

DESIGN FOR A TELESCOPE

Adolph Langsner, Chicago, Ill., assignor to Eugene Dietzgen Company, Chicago, Ill., a corporation of Delaware

Application August 25, 1934, Serial No. 53,063

Term of patent 14 years

To all whom it may concern:

Be it known that I, Adolph Langsner, a citizen of the United States, residing at Chicago, Cook County, Illinois, have invented a new, original, and ornamental Design for a Telescope, of which the following is a specification, reference being had to the accompanying drawing, forming part thereof.

Figure 1 is a plan view of a telescope showing my new design; and

Figure 2 is a side view of the same.

The principal feature of the design resides in forming the adjustable eye piece to a bullet-nosed or streamlined configuration while forming the adjusting nut with rounded crown and edges in harmony with the eye piece.

I claim:

The ornamental design for a telescope as shown and described.

ADOLPH LANGSNER.
